CLAIM

The ornamental design for a tip component for a welding torch, as shown and described.

DESCRIPTION

FIG. 1 is a perspective view of a tip component for a welding torch;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a cross-sectional view taken along line 8-8 in FIG. 2 thereof.

1 Claim, 5 Drawing Sheets
